JAMES TOPP, OF CHICAGO, ILLINOIS, ASSIGNOR TO EBERSON-TOPP, INC., OF CHICAGO, ILLINOIS.

WIND CHEST AND VALVE ACTION FOR ORGANS.

1,419,703.

Specification of Letters Patent. Patented June 13, 1922.

Application filed January 10, 1921. Serial No. 436,064.

To all whom it may concern:

Be it known that I, JAMES TOPP, a citizen of the United States, residing at Chicago, in the county of Cook and State of Illinois, have invented certain new and useful Improvements in Wind Chest and Valve Actions for Organs, of which the following is a specification.

My invention relates to an organ, more particularly to the valve action thereof and its associated parts and the object thereof is to make the valve action including its seat, as a unit and also to make such unit readily removable with the result that the entire valve action may be removed without opening or disturbing the wind-chest. My unit structure is also so made as to be capable of supporting the organ pipes, thereby dispensing with the usual supporting racks. Other novel and advantageous features of construction in my new organ structure will be apparent from the description herein-after given.

In the drawing Fig. 1 is a sectional elevation of a part of an organ embodying my invention. Fig. 2 a top plan view of one of my units inserted in the wind-chest. Fig. 3 a section on the line 3—3 of Fig. 2 but on a larger scale. Fig. 4 an elevation partly in section of my unit. Fig. 5 a detailed view illustrating my unit in connection with one of the larger pipes; Fig. 6 a detailed view similar to Fig. 2 illustrating a modified form of construction of contact plates; and Fig. 7 a section on the line 7—7 of Fig. 6.

Referring to the particular embodiment of my invention herein selected for illustration and description, the wind-chest is of the usual construction and provided with the wind-trunk or inlet 2 and with a top board 3 having series of top openings 4 in vertical line with the series of organ pipes such as the larger pipes 5 and the smaller pipes 6.

The valve action including this seat is made as a unit, the same also serving to support the organ pipes, thereby dispensing with the usual racks especially for the smaller pipes. Each unit is made of such character and size as to be readily insertable into and removable from its hole 4 in the top board of the wind-chest, in which operation the organ pipe may be first removed from the unit, or removed therewith as desired. Moreover, the units of each series are 55 separate physically even as to the electric

wiring so that any one unit of a series is independently insertable in the windchest and independently removable therefrom.

Describing the unit structure illustrated, the same includes a head portion 7 which may be termed the pipe block, whose central body portion enters and substantially fills the opening 4 and has an intermediate flange portion 8 resting upon the top board through the medium of the sealing ring 9 so as to hold the block in its inserted position and to seal said opening. This block is provided with a central passage or wind-way 10 whose upper portion is enlarged and also tapered so as to receive the lower end of the pipes such as the smaller pipes 6 in Fig. 3 and the larger pipes 5 as in Fig. 5. The lower surface of the block adjacent the wind-way 10 forms a seat 11 for a vertically operating valve 12 which in the present instance is controlled and operated pneumatically. This valve is connected to and supported by a diaphragm structure including a top diaphragm 13 and a lower diaphragm 14 connected together at their margins by a ring 15. The lower diaphragm is in turn connected to a ring which is secured to a plate or block 17 constituting a diaphragm support. This support 17 is provided with a chamber 18 communicating with the interior of the diaphragm structure and also with a passage 19 and a chamber 20 in a plate or packing 21 which is interposed between the plate 17 and a magnet block 22. A coiled spring 23 which is located in the chamber 18 normally tends to draw the valve 12 from its seat against the pressure of the air in the diaphragm structure. In the chamber 20 there is located the vertically operating armature 24 controlled by the electro magnet 25 which is secured to and supported by the block 22. This armature controls the lower end of an exhaust passage 26 which extends through the plate 17 and through the short pipe 27 passing through the dowel post 28 and thence passing through the pipe block and to atmosphere at 29. The tube 27 is preferably employed to provide for sealing of the exhaust passage as it runs from the plate 17 to the pipe block 7.

The parts described are removably held or clamped together in suitable manner and in the present instance I utilize brass bolts 30 which serve also as electrical conductors or 110

binding posts for the wires 31 of the magnet and as means for securing electrical contacts 32 upon the tops of the units. These bolts pass through the blocks and plates 7, 17, 5 21 and 22 and also through dowel posts 33 similar to the post 28 which posts are all located between the block 7 and the plate 17. Thus these bolts together with the nuts 34 constitute clamping means and also the 10 necessary electrical connections for the magnets 25. The contacts 32 are normally in contact with the contacts 35 and 36 secured to the top board by the screws 37. The contact 35 is electrically connected to the general 15 return through the wire 38 and the contact 36 is electrically connected to the usual key contact corresponding to this unit by the wire 39.

Describing the valve action; when the key 20 contact is made and the magnet is energized the armature 24 is attracted against the air pressure in chamber 20 tending to hold it in its upper position, whereupon the exhaust passage 26 is open to atmosphere and the air 25 pressure in the diaphragm structure is permitted to escape. As a result, the valve 12 is withdrawn from its seat 11 and the air from the wind-chest is admitted to the organ pipe. In the event that it is necessary 30 to repair or examine any valve action, the organ pipe is first removed or not, as desired, and the entire unit including the valve action and its seat is slightly turned and then withdrawn upwardly from the wind- 35 chest and removed therefrom. The entire structure including the valve seat and valve wherein the trouble generally resides is accessible and under the observation of a repairman. As a result, the valve action can 40 be properly repaired and tested for proper action before it is again inserted in place. Not only this, but this operation does not require the opening or dismantling of the wind-chest which is always a laborious and 45 expensive job. Moreover, I am enabled to repair any one or more of the valve actions and associated parts without putting the organ out of commission.

In the act of removal of the unit structure 50 such structure is rotated slightly so as to carry the contacts 32 out of their locking engagement with the contacts 35 and 36, the latter being offset upwardly at their inner ends as indicated in Fig. 4. The structure 55 is now free to be lifted upwardly out of the top opening of the wind chest and to be removed bodily therefrom. In the act of inserting the structure in place such structure after being inserted into the opening is rotated or moved angularly so as to bring its 60 contacts 32 into engagement with the contacts 35 and 36. These contacts therefore serve both as electric contacts and as means for holding the unit structure in position.

65 The double opposed diaphragms 13 and

14 are very advantageous in practice for several reasons, particularly because, in view of the fact that their margins are not anchored but freely float, the diaphragms (one of which is anchored at its middle portion 70 and the other of which is secured to the valve) have considerable movement and flexibility, thereby assuring perfect seating of the valve and also because the valve is given a greater range of movement. 75

In Fig. 6 I have shown a modified form of construction of contacts according to which the contacts 40 are made somewhat different in shape as compared with the contacts 35 and 36, particularly in that they are provided with stop flanges 41 which limit the angular movement of the unit structure when being inserted in place. As shown in detail in Fig. 7, the contacts may also be provided with locking socket and knob indicated at 42 and 43 whereby they may be held yieldingly in engaged position.

I claim:

1. In an organ, the combination, with a wind chest, of a series of valve actions, each 90 made as a unitary structure and separately bodily insertible in and removable from such chest.

2. In an organ, the combination, with a wind chest having a top opening, of a valve 95 action bodily insertible in such opening and removable therefrom.

3. In an organ, the combination with an organ pipe and a wind chest, of a unitary structure including a valve action bodily insertible in and removable from such chest, 100 said structure having provision for receiving and supporting the pipe.

4. In an organ, the combination with a wind chest having an opening, of a unitary 105 structure including a valve action and a valve seat, such structure being bodily insertible in and removable from such opening.

5. In an organ, the combination with an 110 organ pipe and a wind chest, of a unitary structure including a valve action bodily insertible in and removable from such chest, said structure comprising a block having a windway which receives the pipe, and a 115 valve action connected with the block.

6. In an organ, the combination with an organ pipe and a wind chest, of a unitary structure including a valve action bodily insertible in and removable from such chest, 120 said structure comprising a block having a windway, and a valve action connected with the block, said windway being tapered at its upper end to support the lower end of the pipe. 125

7. In an organ, the combination with an organ pipe and a wind chest, of a unitary structure including a valve action bodily insertible in and removable from such chest, 130 said structure comprising a block having a

windway which receives the pipe, and a valve action connected with the block, said chest having an opening to receive the block and such block having a circumferential 5 flange bearing against the chest to seal the opening and support the block in place therein.

8. In an organ, the combination with an organ pipe and a wind chest, of a unitary 10 structure including a valve action bodily insertible in and removable from such chest, said structure comprising a block having a valve seat and a windway which receives the pipe, and a valve action connected with the 15 block and cooperating with said seat.

9. In an organ, the combination with an organ pipe and a wind chest, of a unitary 20 structure including a valve action bodily insertible in and removable from such chest, 25 said structure comprising a block having the valve seat and a windway which receives the pipe, and a valve action connected with the block and cooperating with said seat, said block also having an exhaust to atmosphere controlled by said valve action.

10. In an organ, the combination with an organ pipe and a wind chest, of a unitary structure including a valve action bodily insertible in and removable from such chest, 30 said structure comprising a block having a windway which receives the pipe, and a valve action connected with the block, said block and valve action being detachably connected together.

35 11. In an organ, the combination with an organ pipe and a wind chest, of a unitary structure including a valve action bodily insertible in and removable from such chest, said structure comprising a block having a 40 windway which receives the pipe, a valve controlling said windway, mechanism controlled by the operator for governing said valve, and means for connecting together the block, valve and mechanism.

45 12. In an organ, the combination with an organ pipe and a wind chest, of a unitary structure including a valve action bodily insertible in and removable from such chest, 50 said structure comprising a block having a windway which receives the pipe, a valve controlling said windway, pneumatically operated mechanism controlled by the operator for governing said valve, and means for connecting together the block, valve and mechanism.

55 13. In an organ, the combination with an organ pipe and a wind chest, of a unitary structure including a valve action bodily insertible in and removable from such chest, 60 said structure comprising a block having a windway which receives the pipe, a valve controlling said windway, valve operating mechanism connected with the valve, a plate supporting such mechanism, spacing means 65 between the block and plate to form a space

for the valve, and means for detachably connecting together the block and plate.

14. In an organ, the combination with an organ pipe and a wind chest, of a unitary structure including a valve action bodily insertible in and removable from such chest, 70 said structure comprising a block having a windway, valve operating mechanism connected with the valve, a plate supporting such mechanism, spacing means between 75 the block and plate to form a space for the valve, and means for detachably connecting together the block and plate, said spacing means consisting of dowel posts and said connecting means consisting of bolts passing 80 through said posts.

15. In an organ, the combination with an organ pipe and a wind chest, of a unitary structure including a valve action bodily insertible in and removable from such chest, 85 said structure comprising a block having a windway which receives the pipe, a valve controlling said windway, valve operating mechanism connected with the valve, a plate supporting such mechanism, spacing means 90 between the block and plate to form a space for the valve, and means for detachably connecting together the block and plate, said connecting means consisting of bolts, and said spacing means consisting of dowel 95 posts through some of which the bolts pass, said plate and block having an exhaust passage to atmosphere passing through one of the posts.

16. In an organ, the combination with an organ pipe and a wind chest, of a unitary structure including a valve action bodily insertible in and removable from such chest, 100 said chest having an opening to receive the structure and such structure comprising a 105 block having a windway which receives the pipe, a valve for controlling said windway, means including an electro-magnet for actuating the valve, and cooperating electrical contacts located on the block and chest 110 respectively and connecting with the magnet.

17. In an organ, the combination with an organ pipe and a wind chest having an opening, of a unitary structure received in 115 said opening and comprising a block having a windway which receives the pipe, a valve for controlling said windway, means including an electro-magnet for actuating the valve, and cooperating electrical contacts 120 located on the block and chest respectively and connecting with the magnet, said contacts being constructed and arranged to hold the block in place.

18. In an organ, the combination with an 125 organ pipe and a wind chest, of a unitary structure including a valve action bodily insertible in and removable from such chest, said chest having an opening to receive the structure and such structure comprising a 130

- block having a windway which receives the pipe, a valve for controlling said windway, means including an electro-magnet for actuating the valve, and cooperating electrical contacts located on the block and chest respectively and connecting with the magnet, said contacts having provision for limiting the rotary movement of the block in the opening when such contacts are together.
- 10 19. In an organ, the combination with an organ pipe and a wind chest, of a unitary structure including a valve action bodily insertible in and removable from such chest, said chest having an opening to receive the structure and such structure comprising a block having a windway which receives the pipe, a valve for controlling said windway, means including an electro-magnet for actuating the valve, cooperating electrical contacts located on the block and chest respectively, and bolts for mechanically con-
- necting together the block, valve and actuating means into a unitary structure and for electrically connecting said contacts and magnet. 25
20. In an organ, the combination with an organ pipe and a wind chest, of a unitary structure including a valve action bodily insertible in and removable from such chest, said structure comprising a block 30 having a valve seat and a windway which receives the pipe, a valve cooperating with said seat, a plate carried by said block, two diaphragms connected at their margins, one of them being stationarily secured at its 35 middle portion to said plate, and the other being connected at its middle portion to said valve, and means controlled by the operator for governing air pressure to said diaphragms.

JAMES TOPP.
